UNITED STATES PATENT OFFICE

2,449,441

TOILET

Arthur G. Agra, Chicago, Ill.

Application September 8, 1947, Serial No. 772,709

5 Claims. (Cl. 4—76)

1

This invention relates to toilets, and has to do more particularly with toilets for use in automobile house trailers and like structures.

In general, automobile house trailers presently in use are not provided with adequate toilets. It is essential that the toilet for an automobile house trailer be leakproof, sanitary and free of any objectionable odors. It is also important that pollution from the toilet of water used for drinking purposes, washing, bathing, or like purposes, be effectively guarded against. Since space is at a premium in an automobile house trailer, it is also desirable that the toilet occupy a minimum of space and be of such character that it may be enclosed to provide a seat or analogous structure, so as to avoid waste space. My invention is directed to the provision of a toilet suitable for use in automobile house trailers and like structures, which toilet will meet all of the above requirements while being comparatively inexpensive. Further objects and advantages of my invention will appear from the detail description.

In the drawings:

Figure 1 is a plan view of a toilet embodying my invention;

Figure 2 is a side view of the toilet of Figure 1, partly broken away and in section;

Figure 3 is a front view of the toilet of Figure 1;

Figure 4 is an underneath view of the piston and associated parts, taken substantially on line 4—4 of Figure 7;

Figure 5 is a sectional view, on an enlarged scale, taken substantially on line 5—5 of Figure 7;

Figure 6 is a sectional view, on an enlarged scale, taken substantially on line 6—6 of Figure 1;

Figure 7 is a vertical sectional view, on an enlarged scale, partly in elevation, of the bowl and the base structure therefor, certain parts being shown in elevation and certain other parts being broken away;

Figure 8 is a sectional view, on an enlarged scale, taken substantially on line 8—8 of Figure 7, certain parts being shown in elevation and certain other parts being omitted for clearness of illustration; and

Figure 9 is a sectional view taken substantially on line 9—9 of Figure 7, certain parts being shown in elevation.

The toilet of my invention comprises a base structure 10 including a cylinder 11 having an upper end portion 12 of inverted cup shape, which is removably secured, conveniently by screws 13, to the lower section 14 of cylinder 11, with an intervening gasket 15. Cylinder 11 is closed at its lower end by a bottom wall 16 and is provided

2

with a central opening 17 extending through its top wall 18.

A bowl 20, formed of a plastic or of any suitable material and which is in general of known construction, is provided with a depending tubular neck 21 which seats upon and is secured on the upper end of cylinder 11, conveniently by screws passing through suitable recessed portions of neck 21 and threading into the cylinder section 12. The opening 22 defined by neck 21 preferably is disposed concentric with opening 17, or substantially so. Bowl 20 is provided, at the upper portion thereof, with a passage 23 extending thereabout and provided with downwardly directed openings, one of which is shown at 24, as is known. A short collar 25 extends upward from bowl 20, at the back thereof, and receives a tubular fitting 26 suitably secured therein. An elbow 27, shown more clearly in Figures 1 to 3, inclusive, is connected to fitting 26 in a suitable known manner and opens therethrough into the passage 23 of bowl 20. A valve seat member 28, in the form of a plug, is threaded into the other end of elbow 27, as shown more clearly in Figure 6. Seat member 28 is provided with a seat element 29 upon which seats a normally closed check valve 30 pivoted at its upper side, at 31, on a web element 32 of the valve seat member 28. It will be noted that valve 30 opens inwardly toward the elbow 27 and closes outwardly toward the outer end of member 28. A water pipe 33 is threaded at one end into the outer end of the valve seat member 28 and opens into bore 34 thereof, the other end of pipe 33 being connected to a T 35. A pipe 36 connects the lower end of T 35 to a water control valve 37 of known construction and operation. The valve 37 seats upon and is suitably secured to a suitable base, such as floor 38 of the trailer or like structure, upon which the base structure 10 also seats. Valve 37 is provided with a control pedal 39 disposed to be depressed by the foot of a person seated upon the bowl 20. A water supply pipe 41, extending from any suitable source of supply of water under pressure, is also connected to valve 37. Normally, the pedal 39 is held raised by spring means and the supply pipe 41 is then disconnected from the conduit comprising the elbow 27, pipe 33, T 35 and pipe 36. When the trailer is parked in a trailer camp, the water supply pipe 41 may be connected to the camp water supply, in a suitable known manner, and when the trailer is on the road the pipe 41 may be connected to the usual water storage tank of the trailer, in a suitable known manner. Instead of the valve 37, any other suitable known

valve means may be provided for controlling communication between the water supply pipe 41 and pipe 36. A valve fitting 43, of known type, is threaded in the upper end of T 35. This fitting 43 comprises an inwardly opening valve normally held seated by a light spring or other yielding means. In the event the water supply to pipe 41 is cut off and the water is drained from that pipe, a partial vacuum would be produced therein. Under such conditions, if the valve 37 were opened, a partial vacuum or suction effect would be produced in the pipes 36 and 33. When that occurs, the suction responsive valve 43 opens so as to admit air into the pipes 36 and 33 thus breaking the vacuum therein. Further, any partial vacuum produced in the pipes 36 and 33 causes the check valve 30 to be held more tightly against its seat, by atmospheric pressure. Accordingly, this check valve 30 and the suction responsive valve 43 cooperates to assure that pollution from bowl 20 of the source of water supply cannot occur. That is, of course, of utmost importance, as is recognized by health authorities.

The opening 17 through top wall 18 of cylinder 11 is controlled by a downwardly opening and upwardly closing valve 45 which is, in general, of known type. This valve comprises a suitably formed strip 46, which may be made of an impregnated fabric, leather, or other suitable material. One end of strip 46 is clamped between wall 18 and a flat plate 47 secured to wall 18 by screws 48, or in any other suitable manner. The screws 48 also pass through head 49 of a bowed leaf spring 50 the free end of which bears against the underface of a metal disc 51 riveted to strip 46 at the underface thereof. The disc 51 is of somewhat greater diameter than opening 17 which normally is closed by the valve 45 held, by the pressure of spring 50, against the underface of wall 18. As will be clear from what has been said, the valve 45 closes upwardly and opens downwardly and normally is held in closed position.

A piston 55 fits snugly within cylinder 11 and is vertically reciprocable therein. This piston 55 is provided, at the underside thereof, with a transverse recess 56 closed, at its under side, by a plate 57 set into the underface of piston 55 and removably secured thereto by screws 58, or in any other suitable manner. The piston 55 is further provided at its underface with a slot 59 intersecting recess 56 and opening, at its outer end, through the circumferential surface of piston 55. Slot 59 receives an arm 60 the inner portion of which extends between the two portions of plate 57, the latter being in the form of two sections or plates. An elongated pin 61 is secured through the inner end of arm 60 and projects from the opposite sides thereof a substantial distance into the slot 56. Arm 60 is provided at its outer end with a collar 65 which fits snugly about an operating shaft 66, to which it is suitably secured, conveniently by means of a dog pointed screw 67. The shaft 66 is rockably mounted through the side walls of a housing extension 68 opening into cylinder 11 adjacent the lower end and at the front thereof. As is shown more clearly in Figure 9, shaft 66 projects a substantial distance beyond each of the side walls of extension 68 and suitable means is provided for effecting a fluid tight seal about shaft 66 where it passes through the side wall of extension 68. To that end I have shown stuffing boxes, each comprising a ring 70 fitting about shaft 66 and secured in a suitable manner, conveniently by means of screws, to the side wall

of extension 68, this side wall being recessed about shaft 66 and receiving a suitable packing 72 compressed by ring 70. Any suitable known means may be provided for effecting a fluid tight seal about shaft 66 where it passes through the side wall of extension 68. It will be clear, from what has been said, that shaft 66 is rockably mounted in the extension 68 and that rocking of shaft 66 will be effective for reciprocating the piston 55 within the cylinder 11. The shaft 66 is provided at each end with a reduced hexagonal stud 74 adapted to fit snugly into a corresponding recess in a socket element 75 at the lower end of an operating lever 76. Preferably, each end of shaft 66 is suitably bored and tapped for reception of a headed screw 78 inserted through socket element 75 and threaded into shaft 66, effective for preventing casual displacement of the lever 76. It will be understood that lever 76 provides convenient means for oscillating or rocking the shaft 66 so as to reciprocate the piston 55 within cylinder 11, and that the lever 76 may be applied to either end of shaft 66, as conditions may require.

The base structure 10 is provided with a projection 80 extending rearward from cylinder 11. This projection 80 is provided with an upper passage 81 opening into cylinder 11 remote from the bottom thereof, and a lower passage 82, of substantially less cross sectional area than passage 81, opening into cylinder 11 adjacent the bottom thereof. The passages 81 and 82 open, at their outer ends, through the flat upper surface of projection 80. A gasket 83 is clamped between the upper surface of projection 80 and a hood 84 at the lower end of an elbow 85, hood 84 being secured to projection 80 in a suitable manner, conveniently by means of screws. A pipe 86 is threaded in the other end of elbow 85 and extends therefrom downward through the floor 38 of the trailer for discharge into a suitable bucket or container beneath the trailer or, if desired, the pipe 86 may be connected by a length of hose to any suitable point of discharge. The pipe 86 and the elbow 85 together constitute a discharge conduit, as will be understood.

The gasket 83 may be formed of an impregnated fabric, of leather, or of any other suitable material. It extends substantially throughout the full area of the top surface of projection 80 and is provided with arcuate slots defining valve members 88 and 89 overlying the outer upper ends of passages 81 and 82, respectively. A metal disc 90 is secured to valve member 88, at the outer face thereof, and a metal disc 91 is secured to valve member 89 at the upper face of the latter. The discs 90 and 91 are conveniently secured to the valve members 88 and 89 by screw means, but may be secured thereto in any other suitable manner. It will be noted that discs 90 and 91 substantially correspond in diameter to the upper ends of the corresponding passages 81 and 82, and the valve members 88 and 89 normally are in lowered position seating on the upper face of projection 80 effective for closing the upper ends of passages 81 and 82. These passages 81 and 82 are thus controlled by normally closed inwardly closing and outwardly opening valves which are independently operable.

Preliminary to use of the toilet, a substantial amount of water should be admitted to the bowl 20 by opening the valve 37, as will be understood. After the toilet has been used, the piston 55 is reciprocated by rocking the lever 76. In the down stroke of piston 55 a partial vacuum created

thereby within cylinder 11 is effective for opening the valve 45, so that the contents of the bowl 20 are discharged into the cylinder 11. On the upstroke of piston 55 valve 45 is closed and the contents of cylinder 11 are discharged through the passage 81 into hood 84, and thence through the discharge conduit comprising elbow 85 and pipe 86. During this operation the valve 31 is held open and the bowl 20 is thoroughly flushed out with clean water, the succeeding down stroke of piston 55 again opening the valve 45 so that the water from bowl 20 is discharged into cylinder 11, from which it is discharged in the succeeding upstroke of piston 55. In that manner, by repeated operation of the piston 55 an appropriate number of times, and thoroughly flushing the bowl 20, the toilet may be maintained in a thoroughly clean and sanitary condition.

In order to prevent formation of a partial vacuum beneath piston 55 during its upstroke, a valve 95 of known type is threaded into the housing extension 68 in alignment with the dog pointed screw 67. This valve 95 is of known type and contains an inwardly opening valve member normally held seated by light spring pressure or other suitable yielding means. The outer end of valve 95 is connected by a tube 96 to a similar valve 98 threaded into elbow 85. The outer end of valve 98 is threaded into the neck of a T 99 included in the tube 96. From T 99 the tube 96 is led upward a suitable distance and preferably passes through the roof of the trailer. During the upstroke of piston 55 air is admitted to the housing extension 68, and thence to the lower portion of cylinder 11, through valve 95. During the down stroke of piston 55 any liquid which may have leaked past the piston into the lower portion of cylinder 11 is discharged from the cylinder through the passage 82, it being noted that the valve 95 closes outwardly so that none of such liquid can be discharged through that valve. The contents of cylinder 11 are thus effectively discharged through the passages 81 and 82 into hood 84, and thence through the elbow 85 and pipe 86. As the materials flow downward through the pipe 86 a siphoning effect is produced which tends to create a partial vacuum within the elbow 85 and hood 84. When that occurs, the valve 98 opens and admits air to the elbow 85, thus breaking the vacuum, in the event a small vacuum effect is produced, and admitting atmospheric air to the hood 84 effective for maintaining the valves 88 and 89 closed, except at such times as the contents of cylinder 11 are being discharged therefrom under pressure through the passages 81 and 82. Since the valves 88 and 89 are independently operable, valve 89 remains closed during discharge of the contents of cylinder 11 through passage 81, and valve 88 remains closed during discharge through passage 82, thereby assuring that a partial vacuum of proper value will be produced above piston 55 during the down stroke thereof, as and for the purposes above described. The elbow 85 also limits the maximum height of water within bowl 20, thereby avoiding risk of flooding, and assures a water seal between bowl 20 and pipe 86, which is conducive to prevention of objectionable odors within the trailer.

Preferably, the lower portion of bowl 20 and the base structure 10 and associated parts are enclosed by a sheet metal housing 102 of appropriate form engaging, at its forward portion, beneath a shoulder 103 of bowl 20, there being a packing element 104 of angle cross section inter-

posed between housing 102 and shoulder 103. Conveniently, the housing 102 comprises a main section 105 having a base flange 106 seating upon floor 38 of the trailer, and a back section 107 having side flanges 108 fitting between the side walls of main section 105 and removably secured thereto, conveniently by means of screws. The main section 105 of housing 102 is provided, at opposite sides of the forward portion thereof, with two openings 110 aligned with shaft 66 and spaced a short distance from the ends thereof, these openings being of appropriate size to accommodate the socket element 75 of lever 76. The opening 110 not in use may be closed by a cap 111, provided with resilient elements 112 of known type, inserted through opening 110 and releasably held in position therein. The housing 102 in addition to providing an enclosure for the lower portion of the bowl and the base structure and associated parts, also serves to impart desired stability to the toilet. The structure is, as a whole, compact and of such character that it may be enclosed in a suitable boxing or casing of a character to be used as a seat, whereby waste space is avoided.

It will be understood that changes in detail may be resorted to without departing from the field and scope of my invention, and I intend to include all such variations, as fall within the scope of the appended claims, in this application in which the preferred form only of my invention has been disclosed.

I claim:

1. In a toilet for automobile house trailers and the like, a base structure comprising a cylinder closed at its bottom, a bowl seating on said base structure discharging into said cylinder, a normally closed downwardly opening and upwardly closing valve controlling communication between said bowl and cylinder, a piston operating in said cylinder, said structure having a projection extending to one side of said cylinder provided with two outlet passages opening at their outer ends through said projection and at their inner ends into said cylinder adjacent and remote from the bottom thereof respectively, normally closed outwardly opening and inwardly closing valves respectively controlling the outer ends of said passages, and a discharge conduit comprising a hood secured to said projection enclosing the outer ends of said passages.

2. In a toilet for automobile house trailers and the like, a cylinder closed at its bottom and having a housing extension adjacent its lower end, a bowl overlying and discharging into said cylinder, a normally closed downwardly opening and upwardly closing valve controlling communication between said bowl and cylinder, a piston operating in said cylinder, a shaft rockably mounted in said extension projecting through the sides thereof with sealing means extending about said shaft, the latter being adapted at each end for reception of an operating lever, and operating connections between said shaft and piston, said cylinder having valved outlet means through which the contents thereof are discharged by operation of said piston.

3. In a toilet for automobile house trailers and the like, a base structure comprising a cylinder closed at its bottom and having at one side a housing extension adjacent its lower end opening thereto, a bowl seating on said base structure discharging into said cylinder, a normally closed downwardly opening and upwardly closing valve controlling communication between said bowl

and cylinder, a piston operating in said cylinder, said structure having two outlet passages opening into said cylinder adjacent and remote from the bottom thereof respectively, normally closed outwardly opening and inwardly closing valves respectively controlling said passages, an operating shaft rockably mounted in said extension projecting through one side thereof, and operating connections between said shaft and said piston, said extension having suction responsive means for admitting air thereto.

4. In a toilet for automobile house trailers and the like, a base structure comprising a cylinder closed at its bottom, a bowl seating on said base structure discharging into said cylinder, a normally closed downwardly opening and upwardly closing valve controlling communication between said bowl and cylinder, a piston operating in said cylinder, said structure having a projection extending from the back of said cylinder provided with two outlet passages opening at their outer ends through said projection and at their inner ends into said cylinder adjacent and remote from the bottom thereof respectively, normally closed outwardly opening and inwardly closing valves respectively controlling the outer ends of said passages, a discharge conduit comprising a hood secured to said projection enclosing the outer ends of said passages and having suction responsive means for admitting air to said hood, said cylinder having a transverse housing extension at the front and adjacent the lower end thereof opening therewith, and a shaft rockably mounted in said extension projecting through one side thereof and having operating connection to said piston, said extension having suction responsive means for admitting air thereto.

5. In a toilet for automobile house trailers and the like, a bowl having an outlet opening at its lower end, a reciprocating discharge pump comprising a substantially vertical cylinder and a piston operating therein, said pump having an intake opening for communication with said outlet opening and a discharge opening, an inlet valve for said pump controlling said intake open-

ing, said valve opening toward said piston and closing toward said bowl, a discharge conduit comprising a member extending from and above said discharge opening, an inwardly closing and outwardly opening pump discharge valve controlling said conduit and disposed below the high point thereof effective for providing a water seal above said discharge valve when the latter is closed, and a normally closed suction responsive valve effective for admitting air to said discharge conduit to break a partial vacuum therein for maintaining the water seal.
